FOLDING COT

Filed April 20, 1925

UNITED STATES PATENT OFFICE

FRED G. MANLY, OF CHICAGO, ILLINOIS, ASSIGNOR, BY MESNE ASSIGNMENTS, TO GEORGE I. GOLDWYN AND HERMAN GOLDWYN, BOTH OF CHICAGO, ILLINOIS, CO-PARTNERS, DOING BUSINESS AS GOLDWYN BROTHERS

FOLDING COT

Application filed April 20, 1925. Serial No. 24,328.

This invention relates to improvements in folding cots and consists of the matters hereinafter described and more particularly pointed out in the appended claim.

5 The primary object of the invention is to provide a folding cot which is strong and rigid and light in weight and which may be quickly and easily set up or taken down and folded into a relatively small compact 10 bundle.

Another object of the invention is to provide a cot of the kind described in which the use of wood as well as folding brace bars between the legs and frame are entirely eliminated.

Still another object of the invention is to provide a cot of the kind mentioned, wherein the entire frame thereof including the side bars or rails, legs and end bars are made of 20 light metallic tubing, the several parts being operatively connected together for compact folding relation by means later described.

These objects of the invention, together with others, as well as the several advantages 25 thereof will more fully appear as I proceed with my specification.

In the drawings:

Fig. 1 is a perspective view of a cot embodying my invention when set up in a position ready for use.

Fig. 2 is a view in side elevation of the frame of the cot on an enlarged scale, showing the relative positions of the parts when in a folded position.

35 Fig. 3 is a horizontal detail sectional view on an enlarged scale, taken on the line 3—3 of Fig. 1.

Fig. 4 is a vertical detail sectional view on an enlarged scale as taken on the line 4—4 of 40 Fig. 1.

Fig. 5 is a side elevation, partly in section of a portion of one end of the cot.

Fig. 6 is a detail vertical sectional view as taken on the line 6—6 of Fig. 5.

45 Fig. 7 is a perspective view of one of the bracket plates connecting one of the end legs to one end of one of the side bars of the cot.

In general, my improved cot comprises 50 a frame and a top fabric, the frame includ-

ing folding side rails or bars, removable end bars, and folding X shaped legs, all made of light weight tubular stock, and said parts are so arranged that when in the extended or set up position a strong rigid cot is provided, 55 and when folded the same comprises a relatively small compact bundle or package, most convenient for shipment or carrying about.

Referring now in detail to that embodiment of the invention illustrated in the accompanying drawings, the frame of my improved cot, is rectangular and is longer than it is wide and comprises side rails 1—1, removable end bars 2—2 and foldable end and 65 intermediate legs 3—3 and 4, respectively, said rails, bars and legs all being made of substantially flat metallic tubes.

The side bars or rails each comprise two sections or parts 5—5 which when the frame 70 is in its open extended position meet or abut at their inner ends in the plane of the intermediate legs 4 and engage the top ends of said legs which provide stops for the meeting ends of said side bar parts or sections, as best 75 shown in Fig. 3. In the outer end of each side bar section is a notch 6 which opens through the end portion of said sections, that part 6^a of said end portion below the notch being shorter than the top part 6^b above the 80 notch as is best shown in Fig. 5. Spaced inward from each notch is a short longitudinally extending slot 7 as is best shown in said Fig. 5.

Each pair of end legs 3—3 is made up of 85 crossed leg members 8 and 9 respectively, the leg member 9 comprising two offset sections 9^a—9^b suitably connected at their adjacent ends by spaced plates 10—10, which also embrace opposite sides of the leg member 8 at 90 a point between its ends and are pivoted thereto as at 11 in Fig. 1. To the top end of the leg member 8 and to the top end of the leg section 9^a are rigidly attached brackets 12 by means of which the end legs are operatively connected to the ends of the side bars or rails of the frame. Each bracket comprises two bracket members 12—12, one of which is shown in perspective in Fig. 7. Each member comprises a body portion 13 and a 100

head portion 14, the body portions of a pair of bracket members embracing the top ends of said legs 8 and leg section 9^a and being secured thereto by rivets 15. The head portions of said bracket members each includes a relatively short lateral extension 16 and a relatively long lateral extension 17, the short extensions of two coacting plates being connected together by a rivet 16^x and the long extensions of said plates being connected together by a rivet 18 which extends through the slot 7 in the ends of the side rail sections and is adapted for movement longitudinally of said slot. The distance between said rivets 15 approximates the distance between the inner ends of the notch 6 and associated slot 7. To add strength to the heads of the bracket plates I provide the ribs 19 as best shown in Fig. 7.

20 The short lateral extension 16 of each bracket member is provided with an offset end flange 16^a which terminates in a longitudinally projecting semi-cylindrical lug 16^b. The lugs 16^b are so positioned that when a pair of brackets is secured in operative position on a leg member and is pivotally connected to the end of a side bar section, said lugs will together form a tubular stem 16^c as best shown in Figs. 5 and 6 to which the cross or end bars 2 may be removably attached as will later appear.

30 The intermediate cross legs 4 are substantially of the same construction as the end legs 3-3 and to the top end of the leg members of said intermediate cross legs I secure T-shaped brackets 20 (see Figs. 1 and 2). Each T-shaped bracket comprises two coacting plates, each having a stem 21 and a head 22 extending at a right angle thereto. The stems of two coacting plates embrace opposite sides of the cross leg members and are riveted as at 23 (see Fig. 2) while the head portions of said plates are spaced apart to receive between them the inner abutting ends 45 of the side rail sections, the said sections being pivotally connected to the ends of the heads by rivets 24. To stiffen said heads, I provide the upset ribs 25 therein. The parts are so proportioned that when the side rail sections 50 are in their aligned and extended positions, the inner ends thereof abut each other in the median plane of the leg members forming the legs 4 and engage the top end thereof as best shown in Fig. 3. This engagement limits 55 the movement of said rails or bars in one direction.

To hold the frame in the extended position I provide the end bars 2-2 which as before mentioned are also of a flat tubular construction and in the inner wall of each bar near the ends thereof are formed openings 26 to fit over the tubular projections 16^c formed by portions 16^b of the bracket plates 12, as best shown in Figs. 5 and 6. In connection with 60 the frame I provide a top member 27 of fabric

such as a good strong canvas. At the sides thereof are longitudinally extending pockets 28 formed by stitching the canvas in the manner well known and in which the side rails are enclosed and at the ends are formed 70 similar pockets 29 to receive the end bars 2-2. The corners of said fabric top and portions of its sides are cut away at a point midway between the ends thereof, as at 30 and 31 to permit movement of the various bracket 75 members.

Assume that the parts are in the folded position as shown in Fig. 2 and that it is desired to open the cot into its extended position ready for use. The sectional parts 5-5 80 of each side rail are swung about their pivotal connection 24 with the T-shaped brackets 20-20 after which the end legs 3-3 are swung about the pivots 18 so as to extend into a position at a right angle to the plane 85 of the side rails and parallel with the intermediate legs 4. With the parts in this position, the side bars are swung laterally away from each other about the pivots 11 of the legs 3 and 4 as an axis, which of course opens 90 the legs into their crossed positions. The end legs are then moved longitudinally outward as far as the slots 7 and rivets 18 will permit them to move so that the rivets 16^x are free to pass the cut away corner end 6^a of the side 95 rail sections to enter the recesses 6 after which said legs are moved bodily inward until the rivets 16^x and 18 engage the inner ends of the recesses and slots 6 and 7 respectively. By this engagement of said rivets with the 100 inner ends of said slots and recesses or notches, the legs are rigidly held against any tendency to fold inwardly toward the side rails and this without the necessity of any folding braces connecting said legs and side 105 rails as are employed in the familiar wood frame and leg cots.

Another advantage is herein gained because the cut away corner parts 30-31 of the canvas or cover 27 may be materially reduced in area, giving a wider head and foot room or space. After the parts are in the position just described the end bars 2-2 are inserted through the end loops or pockets of the fabric top and the ends of the lugs 16^c of the end leg brackets are caused to enter the openings 26 in said end bars 2-2 as before mentioned. In applying the end bars, the fabric is slightly stretched both longitudinally and transversely. Thus it will be smooth and flat and is capable of "giving" under the weight of the occupant so that the cot is comfortable in use. When the end bars are in place they prevent any outward shifting of the end leg brackets so that a strong and rigid construction is provided. To fold up the cot, the operations just above described are reversed, as is apparent.

My improved cot is light in weight and may be folded up into a comparatively small 130

bundle. The frame members and legs being made of flat tubular metallic stock will not bend or break under the rough usage.

While in describing my invention I have referred to certain details of construction, form and arrangement of parts, this is to be taken for the purpose of illustration only so that therefore I do not wish to be limited thereto except as may be pointed out in the appended claim.

10 I claim as my invention:

A folding cot comprising horizontally disposed sectional side frame members, each provided at its ends with a longitudinally extending slot and a longitudinally extending notch, crossed leg members supporting said side frame members, a bracket fixed to each leg member and carrying parallel pins, one of said pins extending through one of the slots in the side frame member and the other pin being adapted to engage one of the notches of the side frame member when one of the leg members is in a certain position and moved lengthwise of the side frame member, 25 a sheet connecting the side frame members, and end bars connected to the sheet and bearing against said brackets for holding certain of the pins in said notches.

In testimony whereof, I have hereunto set
30 my hand, this 27th day of March, 1925.

FRED G. MANLY.
